POCKET COIN CONTAINER

Leo Stein, P.O. Box 1063, F.D.R. Station,
New York, N.Y. 10022

Filed Dec. 29, 1971, Ser. No. 213,799

Term of patent 14 years

Int. Cl. D3—02
U.S. Cl. D87—3 B

FIG. 1

FIG.4

FIG. 1 is a perspective view of a pocket coin container embodying my new design;

FIG. 2 is a side elevational view of the pocket coin container of FIG. 1;

FIG. 3 is a front elevational view of the pocket coin container of FIG. 1; and

FIG. 4 is a bottom elevational view of the pocket coin container of FIG. 1.

I claim:

The ornamental design for a pocket coin container, as shown.
